ART OF MAKING CEMENTITIOUS PRODUCTS.

1,403,542

Specification of Letters Patent. Patented Jan. 17, 1922.

Application filed March 22, 1918. Serial No. 224,046.

To all whom it may concern:

Be it known that I, ALFRED OWEN CROZIER, a citizen of the United States, residing at New York, county and State of New York, have invented certain new and useful Improvements in the Art of Making Cementitious Products, of which the following is a full, clear, and exact description.

This invention relates to the manufacture of cementitious articles, for example, blocks, brick, tile, etc., and is in the nature of an improvement in the art described and claimed broadly in Jaques Patent No. 829,012, in which portions are successively removed from one end of a moist unset cementitious column. The chief object of the present invention is to provide a process which will produce articles or products of high quality rapidly and economically. Another object is to provide a process in which a slushy cementitious mixture, that is, a mixture containing water in excess of the amount needed for hydration of the cement or other cementitious substance, is compacted partly by the pressure of its own weight and partly by pressure from an external source, exerted as the portion from which the articles are to be made is severed from the column. Another object is to provide a process in which the column is subjected to successive impacts or concussions thereby aiding in the desired compacting of the material. A further object is to provide a process in which at least one surface of the severed and removed portion of the column is given a characteristic texture, so to speak, distinctive from that produced by processes or machines in which the bricks or other articles are cast or molded in forms. To these and other ends the invention consists in the novel steps hereinafter described.

In carrying out my improved process or method in the preferred manner the material I employ is a cementitious mixture, for example sand and cement, of a sloppy or slushy consistency, that is to say, containing an amount of water in excess of that needed for the desired hydration of the cement. This consistency of the concrete minimizes the entrapping of air in the mass and the consequent formation of air bubbles, void spaces or cavities therein, and enables me, by subsequent treatment, to practically

eliminate any air bubbles, void spaces or cavities that may be formed.

The cementitious material of the consistency indicated is erected or formed into a vertical column, in an upright tubular shaft or trunk. In this form the difference in the specific gravities of the water and the solid constituents causes the latter to sink and the excess water to rise in the column, thus aiding in the attainment of an effective un-watering of the lower portion of the column. Moreover, the water has a marked lubricating effect, enabling the sand particles to slide or move more freely upon or past each other and thus fit themselves together more closely and compactly. This gives greater firmness, solidity and strength to the mass. At the same time the lower portion is compacted by the weight of the superincumbent mass. The extent of the compacting thus effected, depends, in general, upon the height of the column and may be such as to give such lower portion practically the maximum density that can be attained in a cementitious mixture, but according to the preferred form of the present invention the height of the column is such that the density of its lower portion, due to the weight and compacting or concentrating effect of the portions above, is not only less than the aforesaid maximum density but is indeed substantially less than desired in the articles which are to be formed from said lower portion. The additional "densifying" is effected in the process of severing or removing such lower portion or parts thereof for formation into the bricks, blocks, or other desired articles, or it may be effected in the process of subdividing the severed portion of the column, or partly in each.

The severing of the lower portion of the column, and (preferably) more or less of the desired or necessary additional compacting thereof, are effected by forcing or driving into the column at a proper distance above its bottom a blade or knife of suitable thickness. The column being rigidly supported during this operation, the introduction of the knife may perform at least two important functions. In the first place, it severs a mass or body of the material from the bottom of the column; and in the second place, as will be explained more fully here-

inafter, it may exert a powerful downward pressure on the severed portion or the portion being severed, thereby giving the same the additional compactness necessary or desirable at this stage.

The severed lower portion of the column may now be removed by lowering the pallet or other base on which the column was formed, leaving the upper part of the 10 column resting on the knife; but in practice I prefer to follow the severing knife (which is horizontal) with one or more vertical knives which subdivided the severed portion in vertical planes and at the same time exert 15 more or less lateral pressure on the subdivisions, thereby attaining further densifying or compacting of the same.

The subdividing knife or knives are now retracted to free them from the column, but 20 the upper portion of the column is left resting on the severing knife. The pallet or other member on which the severed lower portion of the column rests is now lowered, and carried away with the article or articles 25 formed thereon as above described. Such articles are made from a cementitious mixture which a few moments before was of a slushy consistency, but nevertheless they are now found to be stiff, compact, 30 dense or stable enough to stand alone without deformation by their own weight although the mass is wholly unset. I thus attain in a few minutes a result which in a straight casting or molding method of using 35 slush-concrete would require at least partial setting or hydration, for its attainment, necessitating a period of time measured by hours or even days.

Upon removal of the articles from the 40 pallet the latter can be replaced, but I prefer to leave the articles on the original pallet during at least a part of the time of hardening or setting of the cementitious material, in which case a fresh pallet is placed 45 in position below the column. The severing knife is now withdrawn, preferably as rapidly as possible. The entire column then falls practically as a whole, and strikes the pallet with sudden force. The heavy impact 50 thus produced is an important aid in compacting the material that now becomes the lower portion of the column, and under favorable conditions may be sufficient to permit a further reduction of the total 55 height of the column.

The operations or steps described above are now repeated, it being understood that during the progress of the work fresh material of the proper consistency is added to 60 the top of the column to compensate for the removals from the bottom, the additions being made preferably before retraction of the severing knife so that the mass of the added material will increase the force of the blow 65 or concussion when the column is allowed to

fall suddenly upon the pallet or other abutment.

It will be readily understood that the apparatus for practicing my method or process can be of very simple character, and it 70 is accordingly necessary to illustrate and describe herein only such parts of the apparatus as are, ordinarily, essential to the practice of the invention in an efficient manner; omitting entirely, for the sake of 75 simplicity and clearness of illustration, the elements or mechanisms for actuating the few moving members or parts of the apparatus.

Referring now to the accompanying 80 drawing,

Fig. 1 is a front view of a vertical shaft or container in which the cementitious column may be formed.

Fig. 2 is a section on line 2—2 of Fig. 1, 85 looking in the direction of the arrows and showing also the severing and subdividing knives in position to enter the column at the bottom thereof.

Fig. 3 is a section on line 3—3 of Fig. 2, 90 looking in the direction of the arrows.

Fig. 4 is a perspective view showing the pallet and the articles (in the present instance bricks) formed on the pallet by severing and subdividing the lower portion of 95 the column.

Fig. 4^a is a view similar to Fig. 4 showing only a single article on the pallet, produced by severing and removing but not subdividing the lower portion of the column. 100

Figs. 5, 6, 7 and 8 are fragmentary side views of the severing knife, showing different forms of the cutting edge thereof.

In using my invention for making brick, the upright hollow shaft 10, in which the 105 column of slushy concrete or cementitious material is formed, is preferably constructed to provide a column about twenty-four inches wide and about eight inches thick, at the base. The shaft is preferably constructed with rigid or inflexible air and water-tight walls, and is closed at the bottom by a removable abutment, as a plate or pallet 11, supported by a vertically movable table 12.

At a proper distance from the bottom (in the present instance, for making brick, the distance is about four inches) the shaft is provided at front and back with horizontal slots 13, 14, to receive the horizontal severing knife 15. Instead of providing mere slots for the horizontal knife the part of the shaft below the path of the knife can be made removable, as a whole or in sections. Vertical slots 16 (opening at the top into said horizontal slots) are provided to receive the vertical subdividing knives 17.

The number and spacing of the subdividing knives depends of course upon the size which it is desired that the articles formed 130

thereby shall have. In making brick from a column twenty-four inches wide I use, ordinarily, nine subdividing knives, spaced equidistantly from each other. Preferably 5 the vertical knives are rigidly attached to the horizontal knife with their forward or cutting edges back of the cutting edge of the horizontal knife a distance which is slightly greater than the thickness of the 10 column at the base.

The shaft contains slush concrete, thereby forming a vertical column of the latter which has its lower portion unwatered and partially compacted as described hereinbefore. 15

The column being thus established, the horizontal severing knife 15 is driven or forced into the lower portion through slot 13 and out through slot 14, thereby completely 20 separating the lowermost part of the column from the upper part. Preferably the knife is of material thickness, say about one-half inch, so that its introduction into the column may effect the desired additional compacting 25 or densifying. Preferably the cutting edge of the knife is beveled. If the bevel is equal on both sides, as in Fig. 2, the compacting effect is divided with substantial equality between the parts of the column below the 30 knife and adjacent to and above the knife. With the bevel entirely on the bottom, as in Fig. 5, the compacting action is expended entirely upon the severed portion of the column, and with the bevel entirely on the top 35 as in Fig. 6 no compacting effect is produced upon the severed portion; whereas with one side beveled more than the other, as in Fig. 7 for example, the compacting effect will be greater toward that side having the greater 40 bevel. In this way it is possible to distribute the compacting effect in the most advantageous manner, as experience may indicate, with due regard to the height of the severed portion. The compacting effect exerted upwardly by the knife is also influenced by the 45 inward slant of the sides of the shaft, making it, in general, impossible for the knife to lift the whole column, with the result that the layer of material above the knife is lifted 50 by the latter into a space of less horizontal cross-sectional area, thereby causing the outer portions of such layer to be crowded inwardly. Thus the said layer of material is in effect subjected to pressure on all six 55 sides,—on its bottom by the knife directly, on its top by the weight of the mass above, and on its sides by the tapering shaft.

The movement of the horizontal knife being continued, the vertical subdividing knives 17 now pass into the vertical slots 16, through the severed portion of the column, and out through the corresponding slots in the rear wall of the shaft, thereby dividing the aforesaid severed portion into bricks, in the present instance ten in number, there

being nine of the vertical knives. These knives are of some thickness; and it will be observed that the severed part of the column is imprisoned on all sides by rigid walls. Hence in forcing a passage through severed 70 part of the column the knives crowd the material out of their way. The individual bricks are thus compacted individually, and the total compacting effected in this manner is proportional to the total thickness of the 75 subdividing knives.

The knives 15 and 17 are now withdrawn until the latter are clear of the column. These movements of the knives have an advantageous trowelling effect, giving smoothly 80 finished surfaces and edges.

The lower portion of the column having been thus severed and trowelled, the knives are arrested with the forward part of the horizontal knife still extending through the 85 column. The table 12 and pallet 11 are then lowered, thus withdrawing the severed and subdivided lower portion of the column downwardly therefrom. The material being in close contact with the underside of the 90 knife and at the same time wet and more or less plastic, the bricks tend to adhere to the knife, and hence as they are freed from the latter their upper faces cling momentarily and numerous small projections, more or less 95 pointed, are thus drawn out as the surface of the bricks breaks away from the knife. This gives the surface a characteristically rough texture, so to speak, which is, however, different in every brick. The result is that 100 when the bricks are laid with these rough faces outward the appearance of the wall is pleasing and the "pattern" does not "repeat" as is the case with blocks or bricks whose "rough" sides are produced by the configurations of the mold in which they are cast. However, a smooth trowelled face can be obtained if desired, by using a severing knife with the underside of its forward portion cut away, as in Fig. 8 for example, so that the 105 110 bricks are not in contact with the knife when they are lowered out of the shaft.

The bricks are now removed from the pallet and the latter replaced, or, preferably, the bricks are left on the pallet on 115 which they are formed and a fresh pallet to close the bottom of the shaft is placed on the table 12, which is then raised. The severing knife is now suddenly withdrawn, thus allowing the entire column to drop 120 bodily upon the fresh pallet. As already explained, the concussion of the fall as the column strikes the pallet has a marked compacting effect upon the lower portion of the column. This concussion is felt not only 125 upon the lower portion but also upon all other portions of the column; so that what is (at any given time) the very top of the column, receives in its descent through the shaft a succession of such compacting 130

shocks, each time with more material, and hence greater weight, above it.

To permit this fall of the column bodily or en masse, the shaft 10 is made with a 5 pronounced downward flare, say as far down as the horizontal slots 13, 14. Below the slots the walls may be truly vertical, so as to give the bricks square corners, but I prefer to have one of the side walls, as 18, 10 Fig. 2, inclined slightly below the slots to facilitate the downward movement of the bricks when the supporting pallet is lowered, as will be readily understood. It will be seen that as the material descends, after 15 withdrawal of the horizontal support or knife 15, the column falls into a space larger than it has previously occupied, spreading out and filling the same, causing the instant rearrangement of the particles, throughout 20 the entire mass, with reference to each other, this effect being markedly facilitated by the lubricating presence of the excess water. This is especially true of the part above the horizontal slots if below the latter 25 there is no flare, or less flare, than above. The result is a marked tendency to produce cracks between the column and the walls of the shaft enclosing the same, and since air cannot reach the cracks from the outer 30 atmosphere the partial vacuum in the cracks can be relieved only by inflow of material from the column. Water and air being lighter and more mobile than sand, water and air bubbles rather than sand are 35 sucked into the cracks, thus aiding in the desired unwatering and "unairing" of the slushy mixture.

The operations described above are repeated, it being understood that fresh 40 material is added at the top of the column, continuously or at intervals, to compensate for the repeated withdrawal of material from the bottom. The process is in effect continuous, as the formation and removal 45 of the articles from the lower portion of the column, though intermittent, occurs at regular intervals and there is no stoppage for recharging the shaft or magazine. The process is also rapid, it being easily possible 50 to make with each apparatus two hundred or more pallet-loads of brick per hour, or say twenty thousand bricks per working day of ten hours. Moreover, the bricks when severed still contain ample water through- 55 out for complete hydration of the cement and hence the cementitious properties of the latter are fully developed.

It is to be understood that the invention is not limited to the specific procedure and 60 apparatus herein described, but can be practiced in other ways without departure from its spirit as defined by the following claims.

I claim:

1. In the art of making cementitious ar-

ticles in which successive sections are removed from the bottom of a concrete column, the steps comprising establishing in an upright hollow shaft or container a column of slushy concrete of a height sufficient 70 to cause its own weight to effect a substantial compacting of its lower portion; compressing the lower portion only of the column while such portion is still in the shaft to further compact or densify such portion 75 and severing a section from the bottom of the column; removing the severed section and permitting the remaining portion of the column to descend; and maintaining the height of the column by the addition of concrete to the upper part thereof.

2. In the art of making cementitious articles in which successive sections are removed from the bottom of a concrete column, the steps comprising establishing in an 85 upright hollow shaft or container a column of slushy concrete of a height sufficient to cause its own weight to effect a substantial compacting of its lower portion; compressing the lower portion only of the column 90 while such portion is still in the shaft to further compact or densify such portion, and severing a section from the bottom of the column; removing the severed section and permitting the remaining portion of the column to descend suddenly by its own weight upon a removable abutment closing the bottom of the shaft whereby the resulting impact aids in densifying the lower part of 95 the column; and maintaining the height of 100 the column by the addition of concrete to the upper part thereof.

3. In the art of making cementitious articles in which successive sections are removed from the bottom of a concrete column, the steps comprising establishing in an 105 upright hollow shaft or container a column of slushy concrete of a height sufficient to cause its own weight to effect a substantial compacting of its lower portion; passing a 110 severing knife of suitable thickness into the unset lower portion of the column to further compact or densify at least a part of such portion and sever a section from the bottom of the column; removing the severed 115 section and withdrawing the knife to permit the column to descend; and maintaining the height of the column by the addition of concrete to the upper part thereof.

4. In the art of making cementitious articles in which successive sections are removed from the bottom of a concrete column, the steps comprising establishing in an 120 upright hollow shaft or container a column of slushy concrete of a height sufficient to cause its own weight to effect a substantial compacting of its lower portion; passing a 125 severing knife of suitable thickness into the lower portion of the column to further compact or densify such portion and sever a 130

- section from the bottom of the column; removing the severed section and withdrawing the knife suddenly to permit the column to fall upon a removable abutment closing the bottom of the shaft whereby the resulting impact aids in densifying the lower portion of the column; and maintaining the height of the column by the addition of concrete to the upper part thereof.
5. In the art of making cementitious articles in which successive sections are removed from the bottom of a concrete column, the steps comprising establishing in an upright hollow shaft or container a column of slushy concrete of a height sufficient to cause its own weight to effect a substantial compacting of its lower portion; passing a severing knife and one or more subdividing knives of suitable thickness into the unset lower portion of the column while the same is still in the shaft to further compact or densify such portion and to sever and subdivide the part below the severing knife; removing the severed and subdivided section of the column and withdrawing the knives to permit the column to descend; and maintaining the height of the column by the addition of concrete to the upper part thereof.
6. In the art of making cementitious articles in which successive sections are removed from the bottom of a concrete column, the steps comprising establishing in an upright hollow shaft or container a column of slushy concrete of a height sufficient to cause it to descend through the shaft by its own weight and effect a substantial compacting of its lower portion; compressing the lower portion only of the column while such portion is still in the shaft to further compact or densify such portion and severing and subdividing the lowermost section of the column; removing the severed and subdivided section and permitting the remaining portion of the column to descend; and maintaining the height of the column by the addition of concrete to the upper part thereof.
7. In the art of making cementitious products in which portions of an upright slushy cementitious column are successively removed from the bottom thereof, the steps comprising passing a severing knife into the lower portion of the column to sever the part below the knife, and lowering the severed part out of contact with the knife whereby a multiplicity of relatively small projections are drawn out on the more or less plastic surface as the same separates from the knife.
8. In the art of making cementitious products in which portions of an upright slushy cementitious column are successively removed from the bottom thereof, the steps comprising passing a severing knife and one or more subdividing knives into the lower portion of the column, and retracting the knife or knives out of the column, whereby the lowermost part of the column is severed therefrom and subdivided and the faces of the subdivisions are trowelled by the surfaces of the knife or knives.
9. In the art of making cementitious products, in which portions of an upright slushy cementitious column are successively removed from the bottom thereof, the steps comprising passing a horizontal severing knife into the lower portion of the column to sever the lowermost part thereof and passing into such lowermost part one or more vertical subdividing knives to subdivide the said part in vertical planes, retracting the knife or knives out of said lowermost part whereby the faces of the subdivisions thereof are trowelled by the surfaces of the knife or knives, and then lowering the said subdivisions out of contact with the horizontal severing knife whereby a multiplicity of relatively small projections are drawn out on the more or less plastic upper surfaces of the subdivisions as the same are separated from the under surface of the knife.
10. In the art of making cementitious articles in which successive sections are removed from the bottom of a concrete column, the steps comprising establishing in an upright hollow shaft or container a column of slushy concrete of a height sufficient to cause its own weight to effect a substantial compacting of its lower portion; passing a severing knife into the unset lower portion of the column to further compact or densify such portion and sever therefrom the part below the knife; removing the severed section of the column downwardly out of the shaft and out of contact with the knife whereby the adhering upper surface of the severed section is roughened as described; withdrawing the knife to permit the column to descend; and maintaining the height of the column by the addition of concrete to the upper part thereof.
11. In the art of making cementitious articles in which successive sections are removed from the bottom of a concrete column, the steps comprising establishing in an upright hollow shaft or container a column of slushy concrete of a height sufficient to cause its own weight to effect a substantial compacting of its lower portion, passing a severing member through said lower portion of the column while maintaining said portion stationary, subdividing said portion in vertical planes while it is still imprisoned, and removing the subdivisions.
- In testimony whereof I hereunto affix my signature.

ALFRED OWEN CROZIER.
